UNITED STATES PATENT OFFICE.

GEORGE R. SIEFKEN, OF NEW YORK, N. Y.

VENTILATOR.

1,026,471.

Specification of Letters Patent. Patented May 14, 1912.

Application filed June 13, 1910. Serial No. 566,572.

To all whom it may concern:

Be it known that I, GEORGE R. SIEFKEN, a citizen of the United States, and a resident of the city of New York, borough of Manhattan, in the county and State of New York, have invented a new and Improved Ventilator, of which the following is a full, clear, and exact description.

This invention relates to ventilators for use with buildings, railroads cars and other structures, and has reference more particularly to a ventilator in which a bodily movable valve is employed to regulate the entrance of air into the structure through the ventilator. The invention also relates to the grouping of a plurality of bodily movable valves in a series, the valve units of which are adapted to operate at different pressures, so that the quantity of air entering through the ventilator will be uniform, regardless of wind velocity at the outside of the ventilator.

The object of the invention is to provide a simple, inexpensive and durable ventilator which can be installed at windows or other structural openings in buildings, railroad cars and the like, which cuts off a minimum of light, the operation of which will not be affected by accumulations of dust and the like, which is practically noiseless in operation, which will prevent an excess of air from entering the structure to be ventilated, regardless of the wind velocity or air pressure at the outside, and which can be constructed in different forms and proportions, to adapt it for various purposes.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a longitudinal section of a ventilator constituting an embodiment of my invention showing the ventilator on a window frame; Fig. 2 is an enlarged transverse section of the window and the ventilator, showing one of the ventilator valves; Fig. 3 is a similar view showing a valve of modified form; Fig. 4 is a similar view showing a valve of further modified form; Fig. 5 is a similar view showing another form of valve; Fig. 6 is a like view show-

ing a further modified form of the valve; and Fig. 7 is a similar view showing another modification of the valve.

Before proceeding to a more detailed explanation of my invention, it should be clearly understood that while I have illustrated for example, in the accompanying drawings, a form of the ventilator which is mounted at the lower part of a window frame, the device can be arranged to be mounted at other parts of a room or other structure to be ventilated. The ventilator may consist of any desired number of units, each of which includes a valve for regulating the flow of air through the ventilator into the room. The number of these units may depend upon special conditions or individual preference. If so desired, a single unit may be employed. I have found that it is possible to overcome certain difficulties found in various present types of ventilators, by employing a valve which is movable bodily, that is, movable in parallelism, as distinguished from a hinged or pivoted valve. The bodily movable valve is best mounted to move in a substantially vertical direction, and its normal position is a horizontal one. Consequently, the ventilator casing can be constructed of comparatively small height and it thereby cuts off little light when positioned in a window frame. By obviating hinges or pivots for the valve it is possible to avoid the difficulty frequently caused by accumulations of dust, which tend to clog the hinges, and also to overcome the possibility of having the hinges rusted by moisture. Such conditions naturally interfere with the proper operation of the ventilator, and tend to render it noisy and uncertain. Certain of the details of construction shown for example herewith, form no part of the invention and can be varied in accordance with individual preference and special conditions, without departing from the underlying spirit of the invention.

Referring more particularly to the drawings, I have shown in Fig. 1 a window frame 10, having a sill 11 and a lower sash 12. The ventilator casing 13 is positioned upon the sill, at the inside of the window, so that the sash can move freely at the outside of the casing. The casing has therein a plurality of partitions 14, which divide it into substantially horizontal passages 15. These are closed at the inner ends of the casing back

16. The outside wall 17 of the casing has a plurality of inlet openings 18 of circular or other suitable form, and each covered by a wire gauze or other screen 19. When the 5 lower sash of the window is partly raised as is shown in Fig. 2, for example, air can enter the openings 18 from the outside.

Above the passages 15, the casing top 20 has substantially vertical openings 21, constituting continuations of the passages 15. 10 The lower ends of the openings 21 are beveled to form valve seats 22, and, at the top, have wire gauze or other screens 23. The screens 19 and 23 are for the obvious purpose of preventing the entrance of dust, insects and the like into the room from the outside.

A cross bar 24 is positioned in each of the openings 21, below the screen 23, and 20 above the valve seat 22. Each has a valve stem 25 depending therefrom and secured in an opening of the cross bar, by suitable flanges 26. At the lower end it has a laterally extended flange 27 constituting a stop. 25 A conical valve member 28 having a central hub or sleeve 29 is movably mounted by means of the latter, upon the valve stem. The valve member has a slightly inwardly inclined rim 30. When the valve is raised 30 to its highest position it will rest at the valve seat 22 to close the passage through the casing and to prevent the entrance of air into the room. The valve tends to float upward under the influence of air pressure at the 35 under side. If the air pressure is such that it is insufficient to overcome the weight of the valve and to raise it, the passage will remain unobstructed. If the air pressure exceeds a predetermined weight, the valve will 40 at once move upward bodily to its closed position. In a ventilator comprising a series of valves the latter are designed to operate at different successive wind pressures. This may be accomplished in several ways. As 45 shown for example, in Fig. 1, I employ a series of valves 28, 28^a, 28^b, 28^c, etc., of different, increasing weights. Consequently, an air pressure or a wind velocity which will 50 close the first of the valves or the second, will not necessarily operate to close the remaining valves. Consequently, the ventilator will automatically regulate the quantity of air entering the room, the number of valves remaining open depending upon the 55 pressure of the air itself. The quantity of air entering the room is thus always uniform. The valve members of a series can be arranged to operate at different air pressures, by the use of springs 31, as shown in Fig. 3. The valve members may thus be of uniform weight and the springs 31 may be of successively increasing strengths. The remaining elements of the ventilator may be unchanged.

60 In Fig. 4 I have shown a modified form

of valve in which a cross bar 32 is employed in the opening 21. The cross bar is provided with a guide sleeve 33 in which a valve stem 34 having at the upper end a head 35, is mounted to move. The valve stem at the lower end carries a valve member 36, and has a flanged end 37 which is soldered or otherwise secured at a central opening of the valve member. The spring 31 shown in Fig. 3 tends to resist the closing of the valve and acts as a cushion or buffer to render the operation silent. If so desired the valve seat 22 may have an annular strip 38 of rubber, felt, or other cushion material secured thereon, against which the valve can seat, and which serves to render the action of the valve noiseless.

In Fig. 5 I have shown a modified form of valve in which a stem 39 is arranged in the passage 15 under the opening 21, and concentric therewith. The valve 40 has a central, downwardly disposed sleeve 41 by means of which it is movably mounted upon the stem 39, and is adapted to float upwardly against the valve seat. The engagement of the center of the valve with the upper end of the stem 39 limits the downward movement of the valve. In Fig. 6 I show a guide sleeve 42 in the passage 15 underneath the opening 21 and concentric therewith. The valve 43 has a central, downwardly disposed stem 44, which is movably received in the sleeve 42. The engagement of the upper end of the sleeve with the valve limits the downward movement of the latter. It is of course free to float upward against the valve seat to close the air passage. It will be noted that in the normal positions of the valves illustrated in Figs. 2, 3, 4, 5 and 6, the air entering through the passage and carrying with it dust, can not deposit the dust at parts of the valves or the guides, where it could accumulate and tend to hinder the operation of the valve.

In Fig. 7 I have illustrated a different form of ventilator, which has a casing 45 provided with inlet passages 46, the outer openings of which are covered by screens 47. Each passage 46 communicates with an opening 48 thereabove, in the top of the casing. An annular member 49 is positioned in the opening 48, and is of angular cross section. It constitutes a valve seat for the conical valve 50 which has rigid therewith a stem 51 extending upwardly. A casing extension 52 is positioned upon the top of the casing proper and has in the rear wall, openings 53 provided with screens 54. Above the openings 53 the casing extension has annular members 55 similar to the members 49 and positioned above the same. A secondary valve or disk member 56 is adapted to seat upon each member 55 and is rigidly secured at the upper end of a valve stem 51, the latter having flanges 57 for

the purpose. The air entering the ventilator casing exerts an upward pressure both upon the valve members 50 and the auxiliary valve member 56, to raise the valves and to seat them against the member 49, to close the passages. By doubling the effective areas of the valve members they can be rendered sensitive to extremely light air pressures.

10 Having thus described my invention, I claim as new, and desire to secure by Letters Patent:

15 1. A ventilator having a casing provided with a plurality of independent air passages, and a plurality of valve members, each arranged to move in one of said passages and adapted to close the same under the influence of air pressure, each of said valve members being adapted to operate at an air pressure different from that required to operate another of said valve members.

20 2. A ventilator comprising a casing having a plurality of inlet openings, independent passages, each communicating with one of said openings, each of said passages having therein a valve seat, and a valve member in each of said passages and adapted to rest against said seat to close its passage, each of said valve members being adapted to operate at an air pressure different from that required to operate another of said valve members.

25 3. A ventilator comprising a casing hav-

ing a plurality of independent air passages therein, and valve members in said passages, 35 said valve members being of different weights, whereby each of said members is adapted to operate at an air pressure different from that required to operate another of said valve members.

40 4. A ventilator comprising a casing adapted to have air pass therethrough, a plurality of valve members each arranged to move from an open toward a closed position, to regulate the amount of air entering through said casing, said valve members being adapted to close under the influence of air pressure, each of said valve members being adapted to operate at an air pressure different from that required to operate another of said valve members.

45 5. A ventilator comprising a casing having a passage therein, and a movable valve in said passage, said valve having a tubular stem extending downwardly therefrom, said 50 casing having associated therewith a guide received in said stem, said stem being open at the lower end only.

55 In testimony whereof I have signed my name to this specification in the presence of 60 two subscribing witnesses.

GEORGE R. SIEFKEN.
